UNITED STATES PATENT OFFICE

VICTOR S. THARP, DECEASED, LATE OF ELMHURST, ILLINOIS, BY BESSIE MARY THARP, ADMINISTRATRIX, OF ELMHURST, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed December 7, 1931. Serial No. 579,416.

The present invention relates in general to telephone systems and more particularly to automatic telephone systems employing the well-known Strowger or other similar switches to establish the telephone connections. The main object of the invention is the improvements of such switches to secure more certain and reliable operation.

A Strowger switch usually employs a so-called release relay which is operated responsive to the operation of the line or impulsing relay when the switch is seized, and which remains operated during the time that the switch is in use to maintain the circuit to the release magnet open. This relay is made slow-to-release by a copper slug on the heel end of the core, or in any other suitable manner, so that it will not release when the line or impulsing relay releases responsive to impulses. Some difficulty has been experienced in properly adjusting the tension of the springs on this release relay so that it will fall back properly when its circuit is permanently opened by the line relay and yet be sufficiently slow to hold up during momentary interruption of its circuit during impulsing. Furthermore, it is often desirable to provide a large number of springs on this relay to control various holding and locking circuits. In the past, the number of springs which could be placed on the release relay has been limited due to the critical adjustment of the relay.

A particular feature of the present invention, therefore, is the provision of means for insuring the continued operation of the release relay during impulsing. According to the invention, this is accomplished by momentarily completing an auxiliary circuit for the release relay during the time its circuit is opened by the release of the line or impulsing relay responsive to received impulses.

The above and other features of the invention may be best understood from a perusal of the following specification when read in connection with the accompanying drawings, comprising Figs. 1 to 3, inclusive, in which

Fig. 1 is a front view of a portion of a Strowger vertical and rotary switch showing

the mechanical arrangement of the double dog and the springs operated thereby, and

Figs. 2 and 3 show by means of the usual circuit diagram the apparatus involved in a telephone connection.

The lineswitch LS indicated in Fig. 2 of the drawings is the well-known rotary lineswitch in which the wipers have no normal position but remain in the position last used. The selector S indicated in Fig. 2 may be a so-called battery-searching selector switch having a directive vertical movement and an automatic rotary movement. A suitable selector switch is disclosed in the co-pending Tharp application, Serial No. 510,680, filed January 23, 1931. The connector C shown in detail in Fig. 3 of the drawings is a code-ringing party-line connector having access to two hundred party lines through two sets of wipers. This connector is somewhat similar to that disclosed in the above-mentioned Tharp application.

Referring now to Fig. 1 of the drawings, the reference character 1 represents a portion of the frame of a two-motion vertical and rotary switch, such as the well known Strowger switch. The shaft 2 which carries the wipers (not shown) is arranged to be stepped vertically by the pawl of the vertical magnet (not shown) engaging the vertical teeth, such as 3. The pawl of the rotary magnet, also not shown, steps the shaft and wipers in a rotary direction by engaging the rotary teeth, such as 4. The stationary dog 9 holds the switch in its vertical direction after the shaft has been stepped off-normal in its rotary direction. The double dog 5 which is pivoted on the vertical pin 8 has a vertical detent 7 which prevents the vertical release of the switch during its vertical movement, and a rotary detent 6 which prevents the rotary release of the switch during its rotary movement. When the vertical magnet is energized, its pawl engages one of the teeth 3 and raises the switch shaft one step in its vertical direction. The double dog 5 is rotated around pin 7 when the shaft is raised since the detent 7 rides to the top of a vertical tooth and then drops to the bottom of the succeeding tooth to hold the switch

100

shaft while the vertical magnet is releasing and disengaging its pawl preparatory to taking another step. Similarly, when the shaft is being rotated responsive to successive energizations of the rotary magnet, the rotary detent 6 rides to the top of a rotary tooth and drops to the bottom of the succeeding tooth thereby rotating the double dog around pin 8.

- 10 The upper end of the shaft 2 passes through a bearing 10 and a hole in the angle bracket 11 which is fastened to the switch frame by means of screws 12. On the bracket 11 are mounted the double dog springs comprising 15 a dead spring 16 and contact springs 14 and 15, separated by suitable insulators. The spring combination is mounted to the bracket 11 by means of screws 13.
- 10 The dead spring 16 and contact spring 15 20 are separated by a bushing at their outer ends and these two springs furnish the tension for keeping the double dog detents in engagement with the vertical and rotary teeth on the switch shaft. The distance between 25 the contacts on springs 15 and 14 is so adjusted that when the switch is being stepped vertically and the double dog detent 7 rides to the top of a tooth, these contacts are closed. Similarly, when the shaft is being rotated, 30 the detent 6 in riding to the top of a tooth rotates the double dog 5 sufficiently so that springs 15 and 16 are operated to the right sufficiently to make the contact between 35 springs 14 and 15. Thus it is seen that whenever the switch shaft and wipers are being stepped either vertically or horizontally, 40 springs 14 and 15 make contact at each step of the switch. The utility of this arrangement will be explained hereinafter in connection with the circuit of connector C shown 45 in Fig. 3 of the drawings. It is to be understood that the arrangement is equally applicable to a selector switch, such as indicated as S in Fig. 2 of the drawings, or to

Referring now to the circuit diagram in Figs. 2 and 3 of the drawings, it will be assumed that the subscriber at substation T desires to establish a telephone connection 50 to the subscriber at substation T₂, whose number it will be assumed is 3155. When the receiver is removed at substation T, a loop circuit is closed over conductors 25 and 26, extending to the rotary lineswitch LS 55 over conductors 30 and 31. The rotary lineswitch LS operates in known manner to select an idle trunk extending to a selector, such as S. When an idle selector, such as S, has been seized, the line and release relay 60 of the selector operate and the release relay returns ground over conductor 36 and through wiper 33 of the rotary lineswitch to hold the lineswitch operated and also to busy the line of substation T in the banks of connectors having access thereto by placing

ground on conductor 28. Responsive to the dialling of the first digit 3, the selector switch S is operated to step the switch wipers opposite the third level of bank contacts, and the switch then automatically rotates to find an idle trunk in this level. It will be assumed that the connector C available over bank contacts 41, 42, and 43 and trunk conductors 44, 45, and 46 is the connector which is seized by selector S over wipers 38, 39, 75 and 40.

Responsive to the extension of the loop circuit over conductors 44 and 46 to the connector C, line relay 55 of the connector operates in a circuit extending from battery, upper winding of relay 55, normally closed springs controlled by armature 52, conductor 44, bank contact 41 and wiper 38 of selector S, conductor 35, the bank contact engaged by wiper 32 and said wiper, conductor 30, line conductor 25, the substation T, line conductor 26, conductor 31, wiper 34 and bank contact, conductor 37, wiper 40 and bank contact 43, conductor 46, normally closed springs controlled by armature 51, lower winding of relay 55, to ground. Relay 55 operates and at armature 56 and its working contact completes an obvious circuit for the release relay 60. Relay 60 operates in this circuit and at armature 65 and its resting contact removes battery potential from the test conductor 45 which was necessary to mark the switch idle to the battery searching selectors, such as S, and at the working contact of this armature places ground on conductor 45 to hold the selector S and lineswitch LS operated. At armature 61 and its working contact it places ground on conductor 140 to prepare various holding circuits as will be explained later. At armature 62 and its working contact it prepares a circuit for itself through the double dog springs 14 and 15. At armature 63 and its working contact it prepares the impulsive circuit, and at armature 64 and its resting contact it opens a point in the release circuit of the switch.

The connector C is a code-ringing party-line connector having access to two-hundred lines over two sets of wipers. The connector is equipped with a minor switch M which selects the set of wipers to be used and the code to be used in ringing the called line responsive to the first digit dialled into the switch. In the assumed case, this first digit is 1. When the subscriber at substation T operates his dial in accordance with the digit 1, line relay 55 releases momentarily responsive to the interruption of the subscriber's loop, and at armature 56 and its resting contact completes a circuit from ground, armature 56 and its resting contact, armature 63 and its working contact, armature 91 and its resting contact, resting contact of armature 100 and said armature, winding of series re- 130

- lay 66 to battery, and in multiple therewith through armature 76 and its resting contact, off-normal spring 72 and its resting contact, winding of rotary magnet 112 of minor 5 switch M, to battery. The rotary magnet of the minor switch energizes and advances wipers 116 and 117 to the first bank contacts. Relay 66 operates in multiple with the rotary magnet 112 without effect at this time. 10 When relay 55 again energizes at the end of the impulse, the circuit to series relay 66 and the rotary magnet 112 is broken and the relay and magnet deenergize.

A diagrammatic showing of the minor 15 switch has been made to illustrate the manner in which the springs 113 to 115, inclusive, are operated. When the rotary magnet 112 is energized, it operates its pawl 143 which engages one of the teeth on the ratchet wheel 20 142, thereby rotating the ratchet wheel 142 one step in a clockwise direction. This rotates wipers 116 and 117 onto the first bank contacts. As the ratchet wheel 142 is rotated, the release detent 144 rides to the top of 25 the tooth on the ratchet wheel and in so doing operates the spring 113 into engagement with the dead spring 115. This closes a passing contact through spring 113, spring 115, and spring 114 while all three springs 30 are in engagement. The release detent 144 rides to the top of the tooth and drops to the bottom of the next tooth, maintaining the three springs in engagement with each other until it again drops to the bottom of the next 35 tooth. The spring 114 is adjusted to follow spring 115 during this movement, but when the release magnet 111 is energized to attract the release detent 144, the detent is moved entirely away from the ratchet wheel thereby 40 operating springs 113 and 115 a sufficient distance so that spring 114 does not follow. The contact between springs 114 and 115 is then broken.

From the foregoing it is seen that when 45 the line relay 55 releases to repeat the first impulse to the magnet of the minor switch, it breaks the circuit of release relay 60 at armature 56 and its working contact, while at the resting contact of this armature it 50 transmits an impulse to the rotary magnet of the minor switch. The rotary magnet energizes and steps the minor switch one step and during this step the release detent 144 is forced outward by the teeth on the ratchet 55 wheel, thereby bringing springs 113, 114, and 115 into contact with each other. This completes a circuit from ground at armature 61 of relay 60 and the working contact of this armature, conductor 140, spring 114, spring 60 115, spring 113, winding of release relay 60 to battery. This circuit is closed momentarily during the time that the initial energizing circuit of relay 60 is opened at armature 56 and its working contact. Thus a momentary impulse of current is sent through

the winding of relay 60 to maintain the magnetism in its core and thereby prevent any possibility of the release of this relay during the time that its circuit is opened when the line relay 55 releases to repeat the impulses. 70

A short interval after the termination of the first impulse series, which in this case consisted of only one impulse, relay 66 releases and at armature 68 and its resting contact completes a circuit from the grounded conductor 140, first bank contact engaged by wiper 116 and said wiper, armature 68 and its resting contact, off-normal contact 145, lower winding of ring-cut-off relay 73, to 80 battery. Relay 73 energizes after an interval and at armature 75 and its working contact prepares a locking circuit for itself. At armature 76 and its resting contact it opens the impulsing circuit to the rotary magnet 85 of the minor switch M, and at the working contact of this armature it prepares the impulsing circuit to the vertical magnet 70 of the connector. The operation of armatures 74 and 77 is without effect at this time. 90

When the subscriber at substation T operates his dial in accordance with the next digit, which in this case is assumed to be 5, line relay 55 momentarily releases and re-operates five times, thereby sending five impulses to vertical magnet 70 over the following circuit: from ground, armature 56 and its resting contact, armature 63 and its working contact, armature 91 and its resting contact, resting contact of armature 100 and said 100 armature, winding of series relay 66 to battery, and in multiple therewith over armature 76 and its working contact, winding of vertical magnet 70 to battery. At the first vertical step off-normal springs 145 open.

but at this time relay 66 is energized and at armature 68 and its working contact completes the locking circuit for relay 73 which extends from grounded conductor 140 in the 105 previously traced circuit over armature 68 and its working contact, armature 75 and its working contact, lower winding of relay 73 to battery. Responsive to the five successive energizations of vertical magnet 70, the 110 switch shaft and wipers are stepped vertically to a position opposite the fifth level of bank contacts. At each step of the switch, the vertical detent 7 of the double dog 5 (shown in Fig. 1) rides to the top of a vertical tooth thereby operating springs 15 and 115 16 so that springs 14 and 15 make contact and complete a momentary holding circuit for the release relay 60 extending from ground at the working contact of armature 62 and said armature, springs 14 and 15 of the double dog spring combination, winding of relay 60 to battery. This circuit is effective during the time that the initial energizing circuit of relay 60 is opened while the 120 line relay 55 is repeating the impulses to the 125

130

vertical magnet. This prevents any possibility of the deenergization of the release relay when its circuit is intermittently opened by the line relay responsive to received impulses.

A short time after the termination of the vertical impulses, series relay 66 releases and at armature 68 and its working contact opens the locking circuit of relay 73. The initial 10 energizing circuit of relay 73 over the back contact of armature 68 is now open at off-normal springs 145. After an interval relay 73 releases and at armature 75 and its working contact opens a point in its own locking 15 circuit, at armature 76 and its working contact it opens the impulsing circuit of the vertical magnet 70, and at the resting contact of this armature it prepares the impulsing circuit to the rotary magnet 71. Off-normal 20 spring 72 opened its resting contact at the first vertical step of the switch and is now in engagement with its working contact.

When line relay 55 is intermittently de-energized in accordance with the digit 5 next 25 dialled by the subscriber at substation T, five impulses are transmitted to the rotary magnet 71 over the following circuit: from ground, armature 56 and its resting contact, armature 63 and its working contact, armature 91 and its resting contact, resting contact of armature 100 and said armature, winding of relay 66 to battery, and in multiple therewith over armature 76 and its resting contact, off-normal spring 72 and its 30 working contact, winding of rotary magnet 71 to battery. The rotary magnet 71 is thereby momentarily energized five times and steps the shaft and wipers in a rotary direction into engagement with the fifth set of 35 bank contacts. At each step of the switch and while the initial energizing circuit of relay 60 is open at armature 56 and its working contact, the double dog springs 14 and 15 are operated by the detent 6 of double dog 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 resting contact it opens a point in the impulsing circuit, at armature 101 and its working contact it prepares a locking circuit for the ring-cut-off relay 73, at armature 102 and its 5 working contact it prepares a circuit to the pick-up relay 80, at armature 103 and its resting contact it opens a point in the test circuit over which selectors having access to the connector switch C test the release trunk conductor for battery potential, at armature 98 and its working contact it prepares a locking circuit for wiper-switching relay 106 which does not enter into the connection being described, at armature 97 and its working contact 10 tact it places ground through armature 108 and its resting contact and wiper 119 on bank contact 125, thereby marking the called line busy to all other connectors having access thereto, and at armatures 96 and 104 and 15 their respective working contacts it completes a ringing circuit to the called line, dependent upon the operation of pick-up relay 80.

The pick-up conductor 108 extends to the 25 code-ringing machine as do the code conductors 146 to 150, inclusive. The pick-up conductor 105 is grounded by the code-ringing machine between codes so that ringing by any one connector cannot be started except at the 30 beginning of the code. This prevents a part of a code being sent out to the called line as a ringing signal. When conductor 105 is grounded at the beginning of a ringing code, relay 80 operates and at armature 81 and its 35 working contact locks itself operated to grounded conductor 140. At armature 82 and its working contact it completes the ringing circuit extending in the assumed case from code conductor 146 and the first bank 40 contact engaged by wiper 117 of the minor switch, wiper 117, working contact of armature 82 and said armature, upper winding of ring-cut-off relay 73, armature 84 and its resting contact, resting contact of armature 74 45 and said armature, armature 96 and its working contact, armature 107 and its resting contact, wiper 118 and bank contact 124, conductor 133 of the called line, through the bells at the party-line substations connected to this 50 conductor of the line, to ground.

When the party-line subscriber hears his code he answers the call by removing his receiver, thereby completing a direct current path through his substation and allowing current to flow through the upper winding of ring-cut-off relay 73 of the connector. This circuit extends from battery at the code-ringing machine over the above-traced ringing circuit to conductor 133, the direct current path through the substation which has answered the call, conductor 132, bank contact 126 and wiper 120, resting contact of armature 110 and said armature, armature 104 and its working contact, armature 77 and its resting contact, resting contact of armature 85 and said armature, to ground. Relay 73 operates and at armature 75 and its working contact completes a locking circuit for itself over its lower winding from ground at armature 101 and its working contact. At armatures 74 and 77 and their respective resting contacts it disconnects the ringing and ring-cut-off circuits, and at the working contacts of these armatures it short circuits the condensers 79 and 78 which are provided to allow a portion of the ringing current to leak back to the calling line as a ring-back signal, and completes the circuit for the back-bridge relay 50 over the called subscriber's loop. At armatures 51 and 52, relay 50 reverses the 70 battery connections to the called line for supervisory or metering purposes, at armature 53 it makes an additional ground connection to the conductor 140, and at armature 54 it opens a point in the circuit of the release magnet of the switch. The connection from the subscriber at substation T has now been established to the desired subscriber at substation T2 on the party-line comprising conductors 132 and 133 and conversation may take 80 place.

At the end of the conversation, when the subscriber at substation T replaces his receiver the loop circuit extending to line relay 55 of connector C is opened and this relay, accordingly, releases. At armature 56 and its working contact it opens the circuit of release relay 60. After an interval relay 60 releases and at armature 61 and its working contact removes one ground connection from conductor 140, but this conductor is grounded at armature 53 and its working contact as long as the called subscriber maintains his receiver off the hook. Assuming that the called subscriber has replaced his receiver, relay 60 completes the release circuit of the switch extending from ground at armature 64 and its resting contact, armature 54 and its resting contact, off-normal springs 57, winding of release magnet 69, to battery. Release magnet 69 operates to bring about the release of the switch and at its armature 151 and resting contact it removes battery from the release trunk conductor 45 so that the switch 100 cannot be seized by a selector until it has completely restored to normal. The release circuit for the minor switch M is also closed from ground at armature 64 and its resting contact, off-normal springs 141 of the minor switch, winding of release magnet 111 to battery. Release magnet 111 operates and disengages the release detent 144 from the teeth of ratchet wheel 142 and allows the minor switch to restore to normal under spring power. The release detent 144 in this case is operated a sufficient distance so that the contact between springs 114 and 115 is opened.

Relays 80 and 95 release when ground is removed from conductor 140 and relay 95 in releasing opens the locking circuit of ring-

cut-off relay 73 thereby allowing this relay to release. When the connector switch has completely restored to normal, off-normal contacts 57 are opened, thereby opening the circuit to the release magnet 69 which deenergizes and again completes the testing circuit to the switch through armature 151 and its resting contact. The release circuit to release magnet 111 of the minor switch M is opened at off-normal springs 141 when the wipers of the minor switch have been restored to normal.

When ground is removed from release trunk conductor 45 at armature 65 and its working contact by the release of relay 60 of the connector, the selector switch S which was held operated by this release ground releases in known manner. All the apparatus used in the establishment of the connection from substation T to substation T₂ on the party line comprising conductors 132 and 133 has now been restored to normal.

The connector switch C shown in Fig. 3 of the drawings is arranged for five-party code ringing. With the strappings of the minor switch banks as shown in the drawings, the five substations on party line comprising conductors 132 and 133 are arranged with three of the bells at the substation connected from the negative line conductor 133 to ground and with the bells at the other two substations connected between the positive line conductor 132 and ground. Codes 1, 3, and 5 are transmitted over conductor 133 to signal the three subscribers whose bells are connected between this conductor and ground, and codes 2 and 4 are transmitted over the positive conductor 132 to signal the remaining two subscribers. On the party line comprising conductors 130 and 131, the bells at three of the substations are connected between the positive line conductor 130 and ground, and the bells at the remaining two substations are connected between the negative line conductor 131 and ground. Codes 1, 3, and 5 are transmitted over the positive conductor 130 to signal the three subscribers whose bells are connected to this side of the line, and codes 2 and 4 are transmitted over the negative line conductor 131 to signal the two subscribers whose bells are connected to this side of the line.

In order that the ringing arrangement and that the manner of selecting the set of wipers to be used in the establishment of the call may be clearly understood, the operation of the connector switch C will be explained on several other different calls. In the connection just explained, code No. 1 was transmitted over the negative line conductor 133 to signal one of the subscribers on this line. It will now be assumed that a subscriber on the party line comprising conductors 130 and 131 is being called. In this case the first digit dialled into the connector C will be

2, 4, 6, 8, or 10, depending upon the party on this line which is being called. It will be assumed that this first digit is 2, in which case the desired subscriber is connected between the positive line conductor 130 and ground. 70

The initiation of the call by the subscriber at substation T and the operation of the lineswitch LS and selector S to extend the connection to a connector switch, such as C, is the same as previously described. When the connector switch C is seized, line relay 55 and release relay 60 operate in the same manner as previously described. Release relay 60 prepares the impulsing circuit at armature 63 and its working contact and at armature 65 and its working contact connects ground to release trunk conductor 45 to make the switch C busy to other selectors having access thereto. In this case, the first digit dialled to the connector C is 2 and the line relay 55, therefore, momentarily releases twice. At each release, an impulse is transmitted from ground, armature 56 and its resting contact, armature 63 and its working contact, armature 91 and its resting contact, resting contact of armature 100 and said armature, winding of series relay 66 to battery, and in multiple therewith over armature 76 and its resting contact, off-normal spring 72 and its resting contact, winding of rotary magnet 112 of the minor switch M to battery. The minor switch M, therefore, takes two steps and moves its wipers 116 and 117 into engagement with their respective second bank contacts. Series relay 66 energizes during the impulse series. 100

A short interval after the impulse series has been terminated, relay 66 releases and at armature 68 and its resting contact completes a circuit extending from the grounded conductor 140, lower winding of wiper-switching relay 106, upper winding of ring-reversing relay 83, second bank contact engaged by wiper 116 and said wiper, armature 68 and its resting contact, off-normal contacts 145, lower winding of relay 73 to battery. Relays 73, 83, and 106 energize in series in this circuit. Relay 106, in energizing, at armature 109 and its working contact locks itself energized to the release trunk conductor 45 through the normally closed springs controlled by armature 98 of relay 95. At armatures 107, 108, and 110, it transfers the connections from wipers 118, 119, and 120 to the second set of wipers 121, 122, and 123. Relay 83 at armature 86 and its working contact completes a locking circuit for its lower winding extending from ground on conductor 140, lower winding of relay 83, working contact of armature 86 and said armature, resistance 93 to battery. At armatures 84 and 85 it reverses the connection of the ringing leads to the line conductors. 120

At the first impulse of the succeeding digit 5, relay 73 locks energized through armature 130

75 and its working contact, and working contact of armature 68 and said armature, as long as the series relay 66 is operated. When this relay releases at the end of the vertical 5 series of impulses, it opens the circuit of relay 73 and allows this relay to release and prepare the circuit to the rotary magnet. The last digit 5 is received and five impulses are transmitted to the rotary magnet of the 10 switch to operate the wipers into engagement with bank contacts 127, 128, and 129 over which access is had to the party line comprising conductors 130 and 131. The operation of the switch for the last two digits is the 15 same as that previously described. Before the series relay 66 releases at the end of the rotary series of impulses, the called party line is tested for busy or idle condition by relay 87 in the same manner as previously described.

Assuming that the line is idle, a circuit is completed for wiper-connecting relay 95 as soon as the slow-to-release series relay 66 releases. Relay 95 operates and at armatures 25 96 and 104 and their respective working contacts completes the ringing and ring-cut-off circuits to the called line. In this case the ringing circuit extends from the battery-connected code-ringing machine, over conductor 30 146, the second bank contact engaged by wiper 117 of the minor switch, wiper 117, working contact of armature 82 and said armature, upper winding of ring-cut-off relay 73, armature 84 and its working contact, 35 resting contact of armature 77 and said armature, working contact of armature 104 and said armature, armature 110 and its working contact, wiper 123 and bank contact 129, conductor 130, through the bells at the substations connected to this line conductor, to ground. Code No. 1 is transmitted over this 40 ringing circuit and operates the bells connected between conductor 130 and ground. The desired subscriber upon hearing his code 45 moves his receiver, thereby completing a direct current path for the upper winding of ring-cut-off relay 73 which includes the above ringing circuit over conductor 130, the direct current path through the called subscriber's 50 substation, conductor 131, bank contact 127 and wiper 121, working contact of armature 107 and said armature, working contact of armature 96 and said armature, armature 74 and its resting contact, working contact of 55 armature 85 and said armature to ground. Relay 73 operates in this circuit and at armatures 74 and 77 cuts off the ringing current, short-circuits condensers 78 and 79, and completes the circuit to back-bridge relay 50 over 60 the called loop. Relay 73 locks itself energized over armature 75 and its working contact to ground at armature 101 and its working contact. The circuit to the desired subscriber on the party line comprising conductors 130 and 131 has now been completed and

conversation may take place. At the end of the conversation, the release of the switch train used in the establishment of the connection is effected in the same manner as previously described.

Assuming now that the calling subscriber at substation T wishes to converse with a subscriber on the party line comprising conductors 132 and 133 whose code signal is code No. 2 and whose bells are connected to the positive line conductor 132. In this case the first digit dialled to the connector switch C will be 3. Responsive to this digit the minor switch M rotates its wipers into engagement with the third bank contacts and the following circuit is completed when series relay 66 releases at the end of the first digit: from grounded conductor 140, lower winding of relay 83, third bank contact engaged by wiper 116 of minor switch M, wiper 116, armature 85 and its resting contact, off-normal springs 145, lower winding of relay 73, to battery. Relays 73 and 83 energize in series in this circuit and relay 83 locks itself energized to grounded conductor 140 over its lower winding at armature 86 and its working contact. At armatures 84 and 85 it reverses the ringing connections to the line conductors. In this case the wiper switching relay 106 is not energized and the normally connected set of 95 wipers 118, 119, and 120 is used.

Assuming that the called line is idle, relay 95 operates in the manner previously described and completes the ringing circuit, after the operation of pick-up relay 80, from battery at the code-ringing machine, conductor 147, third bank contact engaged by wiper 117 and said wiper, working contact of armature 82 and said armature, upper winding of ring-cut-off relay 73, armature 84 and its working contact, resting contact of armature 77 and said armature, working contact of armature 104 and said armature, armature 110 and its resting contact, wiper 120 and bank contact 126, over the positive line conductor 132, through the bells of the substations connected to this side of the line to ground. When the subscriber hearing code No. 2 picks up his receiver, ring-cut-off relay 73 is operated in the above traced ringing circuit including line conductor 132 and through the direct current bridge at the called substation, conductor 133, bank contact 124 and wiper 118, resting contact of armature 107 and said armature, working contact of armature 96 and said armature, armature 74 and its resting contact, working contact of armature 85 and said armature to ground. Relay 73, at armatures 74 and 77, cuts off the ringing current, short-circuits the ring-back condensers 78 and 79, and completes the circuit of relay 50 over the called loop. The connection to the desired called subscriber has now been established and the conversation may proceed. The release of the connection is 123 120

brought about in the same manner as previously described.

Assuming now that the subscriber at substation T wishes to converse with a subscriber on the party line comprising conductors 130 and 131 whose bells are connected to the negative side of the line and who has been assigned code No. 2. In this case the first digit dialled to the connector is 4 and the minor switch M operates its wipers into engagement with the fourth bank contacts responsive to the receipt of this digit. When the slow-acting series relay 63 releases at the end of the series of impulses, a circuit is completed from grounded conductor 140, lower winding of wiper-switching relay 106, fourth bank contact engaged by wiper 116 and said wiper, armature 68 and its resting contact, off-normal springs 145, lower winding of ring-cut-off relay 73 to battery. Relays 73 and 106 operate in series in this circuit and relay 106 at armatures 107, 108, and 110 disconnects the normally-connected set of wipers and connects up the wipers 121, 122, and 123. Relay 106 locks itself energized over its upper winding at armature 109 and its working contact to release trunk conductor 45. Relay 73 releases at the termination of the second series of impulses to transfer the circuit to the rotary magnet of the switch as previously described, and the remaining digit 5 is dialled to operate the connector into engagement with bank contacts 127, 128, and 129.

Assuming that the called line is idle, wiper-connecting relay 95 operates in the manner previously described and locks itself energized to grounded conductor 140. At armatures 96 and 104 it completes the ringing circuit which in this case extends from battery through the code-ringing machine, over conductor 147, fourth bank contact engaged by wiper 117 and said wiper, working contact of armature 82 and said armature, upper winding of ring-cut-off relay 73, armature 84 and its resting contact, resting contact of armature 74 and said armature, armature 96 and its working contact, armature 107 and its working contact, wiper 121 and bank contact 127, conductor 131, and to ground through the bells of the substations connected to the line conductor 131. When the desired party hears his code, which in this case is code No. 2, he removes his receiver from the hook thereby completing the circuit for ring-cut-off relay 73 which includes the above ringing circuit and extends through the direct current bridge at the called subscriber's substation, conductor 130, bank contact 129 and wiper 123, working contact of armature 110 and said armature, armature 104 and its working contact, armature 77 and its resting contact, resting contact of armature 85 and said armature to ground. Ring-cut-off relay 73 energizes in this circuit and locks itself to ground at armature 101 of the wiper-connecting relay

95. At armatures 74 and 77 it disconnects the ringing circuit, short-circuits the ring-back condensers 78 and 79, and completes the circuit for relay 50 over the called loop. The connection has now been completed to the desired called subscriber and conversation may proceed. Release takes place in the same manner as previously described.

It will be seen from an inspection of the multiplying of bank contacts engaged by wiper 116 of minor switch M that there are four control conductors connected to the first four bank contacts and that these conductors are multiplied to the remaining bank contacts. Thus there are four possible ways in which the reversing relay 83 and the wiper-switching relay 106 may be operated. When the digits 1, 5, and 9 are dialled to the minor switch, neither relay 83 nor relay 106 is operated and codes 1, 3, and 5, respectively, are transmitted over the negative line conductor 133. In case the digit 3 or 7 is dialled, relay 83 is operated and codes 2 and 4, respectively, are transmitted over the positive line conductor 132. This takes care of the five subscribers on the party line comprising conductors 132 and 133. Similarly, if the digit 2, 6, or 10 is dialled, both relays 83 and 106 are operated and codes 1, 3, and 5, respectively, are transmitted over the positive line conductor 130. In case the digit 4 or 8 is dialled, relay 106 alone is operated and the codes 2 and 4, respectively, are transmitted over the negative line conductor 131. This takes care of the five subscribers on the party line comprising conductors 130 and 131.

From the foregoing explanation of the operation of the connector switch C, it is apparent that arrangements have been made to momentarily complete auxiliary holding circuits for the release relay of the switch during the intervals when its initial energizing circuit is opened by the release of the impulsing relay responsive to received impulses. This insures the continued operation of the release relay and allows a greater number of springs to be placed on this relay. Also it eliminates the critical adjustment of the spring tension, since sufficient tension may now be placed in the springs to insure proper release of the relay when its circuit is permanently opened and still insure continued operation of the relay during impulsing.

What is claimed is:

1. In an automatic switch, a line relay and a release relay, a circuit for said release relay closed when said line relay operates responsive to the seizure of said switch, means controlled by said line relay responsive to received digit impulses for operating said switch, and means responsive to the operation of said switch for completing an auxiliary holding circuit for said release relay during the intervals when said first circuit is

opened by the release of said line relay responsive to received impulses.

2. In an automatic switch, a line relay and a release relay, a circuit for said release relay closed when said line relay operates responsive to the seizure of said switch, means controlled by said line relay for operating said switch responsive to received digit impulses, a release circuit for said switch controlled by 10 said release relay, an auxiliary holding circuit for said release relay, and means responsive to the operation of said switch for momentarily closing said holding circuit each time said first circuit is opened due to the 15 release of said line relay responsive to received impulses to prevent the release of said release relay and the closing of said release circuit during impulsing.

3. In an automatic switch, a line relay and 20 a release relay, a circuit for said release relay closed when said line relay operates responsive to the seizure of said switch, means controlled by said line relay for operating said switch step by step responsive to received 25 digit impulses, an auxiliary circuit for said release relay, and means operated by said switch during each step for completing said auxiliary circuit.

4. In a two-motion automatic switch, a 30 line relay and a release relay, a circuit for said release relay closed when said line relay is operated, means for releasing said line relay in accordance with digit impulses, two operating magnets for operating said switch 35 in its two movements, respectively, under control of said line relay, an auxiliary circuit for said release relay, and means mechanically operated by said switch each time one of 40 said magnets is energized for completing said auxiliary circuit.

5. In an automatic switch, a line relay and a release relay, a circuit for said release relay closed when said line relay is operated, means for releasing said line relay in accordance 45 with digit impulses, thereby intermittently opening the circuit to said release relay, means controlled by said line relay for operating said switch step by step, an auxiliary holding circuit for said release relay 50 including a pair of contact springs, and mechanical means for operating said springs to close said auxiliary holding circuit each time said switch is operated one step.

6. In an automatic switch, a rotatable 55 shaft, means for rotating said shaft step by step, a detent for holding said shaft during said operation, a release relay for controlling said switch, and means controlled by said detent for completing a momentary circuit 60 for said release relay each time said shaft is advanced one step.

7. In an automatic switch, a vertically 65 movable shaft, means for operating said shaft step by step in its vertical movement, a detent for preventing the release of said shaft

during said operation, a release relay for controlling said switch, and means controlled by said detent for completing a momentary circuit for said release relay each time said shaft is advanced one step.

8. In an automatic switch, a shaft, means for operating said shaft vertically, means for rotating said shaft, a double dog for preventing the vertical and rotary release of said shaft, a relay for controlling the release of said switch, and means controlled by said double dog for completing a momentary holding circuit for said relay each time said shaft is operated in either of its movements.

9. In an automatic switch, two operating magnets each having a pawl, a shaft having vertical and rotary teeth engaged by said pawls, respectively, to operate said switch in its two movements, a double dog having two detents engaging said vertical and rotary teeth, respectively, a line relay and a release relay, a circuit for said release relay closed when said line relay is operated, means for releasing said line relay in accordance with digit impulses to control said operating magnets, said circuit being opened each time said line relay releases, an auxiliary circuit for said release relay, and means operated by the double dog when said switch is stepped in either of its movements for closing said auxiliary circuit.

In witness whereof, I hereunto subscribe my name this 4th day of December, 1931.

BESSIE MARY THARP,
Administratrix of the Estate of Victor S. Tharp, Deceased.
